UNITED STATES PATENT OFFICE.

HENRY G. SWEITZER, OF DETROIT, MICHIGAN.

RADIATOR WALL SHIELD.

Application filed May 12, 1924. Serial No. 712,779.

This invention relates to radiator wall shields and the invention consists in the structural features and arrangement of parts hereinafter set forth and illustrated in the 5 drawing.

Figure 1 is a perspective view of the improved shield.

Figure 2 is a view of same in end elevation when it is in a position to use.

10 Figure 3 is a rear view of the invention.

Figure 4 is a section on the line 4—4 of Figure 3.

15 In these views the reference character A designates an ordinary hot water or steam radiator and A' a wall to which said radiator is adjacent.

The improved shield comprises a top portion formed by overlapping sheet metal plates B and C and a rear portion formed 20 by overlapping sheet metal plates B' and C'. Said top portion is adapted to be superposed on a radiator, as seen in Figure 2, and the rear portion is adapted to project downwardly between the radiator and the adjacent wall. The lower marginal portions 25 of the rear sheets B' and C' are preferably bent at an obtuse angle to the main portions of said sheets and bear upon the wall A'.

The plates B and B' are preferably parts 30 of the same sheet of material, as are likewise the plates C and C'. The units B B' and C C' are connected and reinforced preferably by rolling to a tubular form the integrally joined edge portions of the plates 35 B and B' together with the similarly joined edge portions of the plates C and C', and by further rolling together, as at F, the front edges of the plates B and C. The telescoping tubular portions of the two units 40 thus formed engage each other loosely enough to permit a relative sliding adjustment of said units to vary the length of the shield.

Integral with opposite ends of the sheets 45 B and C are end pieces H, formed by bending said sheets downwardly so as to cover to some extent, the radiator extremities. The rear edges of the walls H of the shield bear against the remote ends of the sheets 50 B' and C' and are formed with flanges H², bent at a right angle to said end walls to overlap the sheets B' and C'. Preferably the flanges H² are permanently secured to the sheets B' and C' by extending tongues 55 J on said sheets through apertures in the flanges.

Preferably a rod or wire K extends downwardly at a rearward inclination in a plane intermediate the length of the radiator from the top plate B to the rear plate B', this connection serving to hold the connected parts firmly in engagement with the radiator. 60

It will be evident that the described shield is adapted by the sliding engagement of its 65 parts for use on radiators of different longitudinal dimensions. By varying the extent to which the two units B B' and C C' overlap the length of the shield may be increased or diminished, the telescopically engaged 70 tubular portions E and F permitting relative sliding adjustment of said units, and maintaining them properly aligned.

What I claim as my invention is:—

1. A radiator wall shield formed by two 75 overlapping sheet metal units, each comprising a top member and a rear member depending therefrom, said units having folded extensions from the angles of intersection 80 of their members, said extensions being rolled into sliding engagement, and the front edges of said units also being rolled into sliding engagement.

2. A radiator wall shield formed of sheet-metal and comprising a top member having an integral downwardly bent end portion, forming an end wall of said shield, and further comprising a rear member depending from and carried by said top member, the rear edge portion of said end wall having 90 interlocking engagement with said rear member.

3. A radiator wall shield formed of sheet material and comprising two slidably engaged units, each unit consisting of a top plate and a rear plate depending therefrom, and each unit having the upper portion of its rear plate and the rear portion of its top plate folded one upon the other in an overlapping relation, said folded portions of the two units being slidably interlocked lengthwise of the units to provide for longitudinal extensibility of the shield. 100

4. A radiator wall shield formed of sheet metal, and comprising two slidably engaged units, each unit consisting of a top member and a rear member formed in one piece with and depending from said top member, said units being interlocked in sliding engagement, one with the other, substantially at 105 the intersections of their top and rear members. 110

5. A radiator wall shield formed by two overlapping units, each comprising a top member and a rear member depending from the top member and cooperating therewith to form tubular portions, said tubular portions telescopically engaging each other permitting a relative sliding adjustment of said units, and an end wall depending from the top member of each of said units having flanges overlapping and secured to the rear member of each unit.

In testimony whereof I affix my signature.

HENRY G. SWEITZER.
